UNITED STATES PATENT OFFICE.

GEORGE P. HAYNES, OF JERSEY CITY, NEW JERSEY, ASSIGNOR TO FRANKLIN M. PATERSON, OF JERSEY CITY, NEW JERSEY, AND JOHN H. ALLEN, OF NEW YORK, N. Y.

VALVE.

1,122,499.

Specification of Letters Patent. Patented Dec. 29, 1914.

Application filed September 20, 1913. Serial No. 730,842.

To all whom it may concern:

Be it known that I, GEORGE P. HAYNES, citizen of the United States, and resident of Jersey City, county of Hudson, and State of New Jersey, have invented an Improvement in Valves, of which the following is a specification.

The object of my invention is to provide a simple and inexpensive form of valve more especially intended for use in steam heating systems, and more commonly known as a radiator valve.

My object is further to so construct the valve that it may be quickly opened and closed; is self cleaning and may also be easily reground without dismantling it.

While my improved valve is particularly useful in steam heating apparatus, it may be used for most purposes where a quick acting valve is desirable.

More specifically, my invention consists of a cylindrical body having an interiorly arranged cylindrical valve seat through which are provided the inlet and outlet ports, and combined therewith, a valve piece constituting a segment of a cylinder having its outer surface contacting with the valve seat of the body, a rock shaft journaled in the body and having a radial part forming a yielding connection with the valve piece and provided on the end with an operating handle, and a spring arranged between the rock shaft and the valve piece whereby the latter is normally held against its seat and all objectionable looseness prevented.

My invention also consists in providing the body with means for introducing a regrinding fluid material, such as oil and flower of emery, and so arranging the operating handle that it may be reversed, whereby in one position it operates the valve piece between definite limit stops on the body and in the other position has capacity for rotating the valve piece within the body without restriction by the limit stops.

My invention also embodies features more fully described hereinafter; and comprehends among other things, details of construction which, together with the structures above specified, will be better understood by reference to the drawings, in which:—

Figure 1 is a sectional view of my improved valve taken on line $y-y$ of Fig. 2; Fig. 2 is a cross sectional view of the same on line $z-z$ of Fig. 1; Fig. 3 is a sectional

view of the same on line $x-x$ of Fig. 2; Fig. 4 is a sectional view through a portion of the body on line $s-s$ of Fig. 2; and Fig. 5 is an elevation of the indicator plate removed from the body.

2 is the body of the valve and is formed in cylindrical shape with an inlet and an outlet, respectively having ports opening into the interior. As, under different conditions to be described hereinafter, either opening 65 may be assumed as the inlet or outlet, I will for the more convenient description assume that 6 is the inlet and 7 the inlet port; and that 4 is the outlet and 5 is the outlet port. The interior of the body is provided with a 70 cylindrical valve seat 3 which, preferably, constitutes a whole circle. One end of the body is cast solid and the other or open end is closed by a head or bonnet 8 which is screwed or otherwise held in place, and may 75 be provided with a suitable stuffing-box 9 through which the rocking stem 19 of the valve operating part extends.

The valve piece 12 is made as if formed from a segment of a cylinder, and has a 80 curvature which exactly fits the curvature of the valve seat 3 of the body. It also has a cylindrical recess or socket 13 arranged at its inner part and directed radially toward the axis of the rock shaft 14. The rock 85 shaft 14 has a journal 18 at one end rotating in a bearing 11 in the closed end of the body 2; and its other end has a spindle or stem 19 which extends through the stuffing-box 9 and journaled in the bonnet or head 8 and 90 in the annular gland 10 thereof which is especially adapted to compress the packing. The rock shaft 14 also has a radial part 15 which is cylindrical on its end, and fits the recess 13 on the valve piece 12; and moreover, has a recess or hole 16, in which a spring 17 is shieldingly located and adapted for pressing radially outward to force the valve piece against the valve seat.

A handle or crank arm 20 has a hub 100 21 fitting upon the end of the stem 19 and secured thereto by a pin 22; and also has a pointer 23 which restricts the throw of the crank arm by coming into contact with limit stops 25 on the valve body, and corresponding to the fully "open" and fully "shut" positions. The pointer also traverses the scale 24 which is attached to the side of the body to indicate the relative positions of the valve piece with respect 105 110

to the inlet port. In Fig. 2, the valve is shown as closed and when the rock shaft 14 is rotated to the right, the valve is opened. The port 7 remains open all the time; and where a considerable steam pressure is to be controlled, this is as it should be, because the pressure of the spring 17 is supplemented by the pressure of the steam to keep the valve piece 12 tightly upon its seat and prevent leaking. It will be manifest, however, that by a slight readjustment of the handle upon the stem, the valve piece may be made to control the port 7 instead of the port 5. It is also evident that the steam or gas may be admitted by the port 5 in cases where a low pressure or a vacuum will prevail in some types of apparatus. If a vacuum is present on the port 5, the valve piece 12 will be forced upon its seat as before, but by the superior atmospheric pressure. If a low pressure were exerted in the port 5, then the spring 17 would have to be sufficiently strong to hold the valve piece in position. In this case also, any loose play between the parts 15 and 12 will permit the valve piece to act as a safety valve or check valve to relieve any excessive pressure. While these reversal arrangements of the valve may be suitable for special uses, the ordinary use will assume the steam or other pressure to be exerted within the chamber of the body and to hold the valve piece upon its seat as first above described.

The valve piece has its edges sharp at the ends of the curved surface and these act excellently as scrapers for removing any scale or deposits which may become deposited upon the valve seat; and this may at any time be removed by rotating the valve piece fully within the valve body, as hereinafter described.

It will be noted that I have provided the gland or bushing 10 with notches 29 and the hub 21 of the crank arm with crown projections 30 which, when the crank arm is removed, may, by reversing the hub, engage the notches in the gland and be employed as a wrench to screw it in or out for adjustment. I also provide the body with a boss 26 (Figs. 2 and 4) and this provides an opening with branch apertures 28 into the surface of the valve seat 3, through which a lubricant may be introduced, or oil and flowers of emery of other vitreous substance for enabling the regrinding of the valve piece to its seat when necessary. The opening in the boss may be closed normally by a screw plug 27. When the valve is to be reground, the plug 27 is removed and the grinding composition inserted, the crank arm 20 is removed and reversed so as not to be restricted by the

stop lugs 25, and then rotated to carry the valve piece through 360° and thereby regrind the whole interior valve seat. It will be understood, however, that while it is not necessary to fully rotate the rock shaft and valve piece, the best regrinding will be secured by complete revolutions, as in such case all surfaces will receive the same treatment. When the regrinding has been accomplished, the crank arm is readjusted to its original position and the valve is then restricted as indicated by the indicator plate. It will be understood that the position of the pin hole in the hub 21 of the crank arm should be such that, when the arm is reversed, the projections 30 will not engage the gland notches 29, as otherwise the arm could not be rotated without disturbing the gland.

I have shown my improved valve in the form I have found satisfactory in practice, and while I prefer the details thereof to be made as shown, I do not restrict myself thereto, as such details may be modified without departing from the spirit of the invention.

Having now described my invention, what I claim as new and desire to secure by Letters Patent, is:—

In a valve, the combination of a body having a cylindrical shaped valve seat through which a port extends, and said body also having a second port opening into its interior, a removable head forming a closure for said body and provided with an apertured flange projecting into the interior of said body to form a bearing, a rock shaft journaled at one end in said body and at the opposite end journaled in said flange bearing and extending to the outside of the body, a valve piece having a curved contacting surface conforming to the contour of the cylindrical seat and also having a recess oppositely disposed with respect to said curved surface, a radially disposed tubular projection formed integral with said shaft and having substantially the same diameter as said shaft, said projection having its open end within said valve piece recess, a spring located within said radial projection and bearing against said valve piece, suitable packing within a portion of said head and encircling said shaft, a crank arm secured to the stem of said rock shaft for moving said shaft from one position to another, and means to limit the movement of said crank arm in either direction.

In testimony of which invention, I hereunto set my hand.

GEORGE P. HAYNES.
